UNITED STATES PATENT OFFICE.

CHARLES S. DONEY, OF COLUMBIA FALLS, MONTANA, ASSIGNOR OF ONE-THIRD TO CHARLES H. FOOT, OF KALISPELL, MONTANA, AND ONE-THIRD TO GEORGE D. WATT, OF COLUMBIA FALLS, MONTANA.

CURRENT-MOTOR.

984,266.

Specification of Letters Patent. Patented Feb. 14, 1911.

Application filed April 5, 1910, Serial No. 553,602. Renewed December 22, 1910. Serial No. 598,822.

To all whom it may concern:

Be it known that I, CHARLES S. DONEY, a citizen of the United States, residing at Columbia Falls, in the county of Flathead 5 and State of Montana, have invented certain new and useful Improvements in Current-Motors, of which the following is a specification.

My invention relates to certain new and 10 useful improvements in current motors and the object of my invention is to utilize the currents of rivers and streams for the purpose of producing power which may be utilized in any desired way.

15 With this object in view my invention consists in certain constructions, combinations and arrangement of parts, the preferred form of which will be first described in connection with the accompanying drawings 20 and then the invention particularly pointed out in the appended claims.

Referring to the drawings wherein the same part is designated by the same reference numeral wherever it occurs: Figure 1 25 is a perspective view showing one form of my invention in position on a stream; Fig. 2 is a side view of the boat or pontoon; and Fig. 3 is a section, taken on line 3—3 of Fig. 2, looking in the direction of the arrow.

30 4, 4 designate a pair of piers, one constructed on each side of the stream and projecting into the stream so that an eddy is formed behind each pier. In the form shown, these piers also carry the operating mechanism.

35 5 designates a cable which extends from the top of one of the piers to the top of the other, and on this cable runs a traveler 6, the traveler being in the form of a block 40 7, on the top of which are mounted a pair of pulleys 8, which run on the cable 5.

9 is a boat structure of any desirable form, preferably and as shown, the same being flat-bottomed and square-ended, with the 45 bow 10 inclined. I have also shown this boat as being decked over by the deck 11, making the same water-tight. Extending downward from this boat or scow are the plates 12, which, in the form of my invention shown, are secured to the sides of the scow. The number and location of these plates may be varied, as desired.

50 13 designates a cable which is secured at

one end of the traveler 6 and at the other end to an eye 14 mounted in the center of 55 the boat or scow. The cable 13 passes beneath a U-shaped iron 15 mounted on the bow of the boat or scow to limit the angle which the boat can be turned to the direction of current of the stream. 60

In the construction so far described, it will be seen that when the boat or scow is turned at an angle to the flow of the stream that the impact of the water upon the plates 12 will cause the scow to move 65 across the stream, the direction of movement being toward the side of the stream, toward which the bow points; as for example, in Fig. 1, the current of the water on flowing in the direction indicated by the arrow 70 16, will cause the scow to move in direction of the arrow 17. If now the scow is turned so as to point toward the opposite bank from that toward which it points in Fig. 1, then the scow will, under the influence of the 75 current, move in a direction opposite the arrow 17. In order to utilize this movement of the scow under the influence of the current and to cause the angle thereof to be automatically changed as the scow reaches 80 each bank of the stream, I provide a pair of eyes 18 on the sides of the scow to which are connected the ends of a cable 19, the cable running over a pair of pulleys 20 on the underside of the traveler block 7, the cable 85 then running around a pulley 21 on one of the piers and over a pair of pulleys 22, 23, on the other pier from which it passes around the pulley 24 of an air compressor or the like indicated at 25. 90

Preferably, and as shown, I provide a pair of springs or other form of buffer 26, one on each side of the bank extending over the eddy formed by each of the piers 4, which buffers are in position to be struck 95 by the forward portion of the scow as it swings into the eddy.

The operation of my motor is as follows: Supposing the scow is moving toward the left-hand bank, as shown in Fig. 1, it will 100 continue to move in this direction until it passes into the eddy formed behind the left-hand abutments 4 and strikes the buffer 26. As the scow moves across the stream, it will cause the cable 19 to travel in the direction 105 of the arrows and consequently drive the

2

pulley 24 of the air compressor or other engine. This driving movement will cause a pull to be exerted upon the eye 18 on the upstream side of the scow and hold the scow 5 angularly to the stream, the amount of such angular movement being limited by the cable 13 and the iron 15. When the scow passes into the eddy or dead water, and strikes the spring buffer 26, it will start the 10 scow to turn and to point its bow toward the opposite shore. This turning is then completed by the momentum of the fly-wheel 24, which, as it continues to rotate, will give slack to the cable connected to the 15 upstream side of the scow and pull on the cable from the downstream side of the scow. This pulling and consequent turning of the scow will cause the bow to project out of the eddy or dead water and as soon as the current 20 strikes one of the plates 12, it will cause the scow to complete its turning movement and assume a position opposite that shown in Fig. 1, or pointing toward the right-hand shore. The current will now force the scow 25 across the stream when the operation just described will be repeated.

I realize that considerable variation is possible in the details of construction and arrangement of parts without departing 30 from the spirit of my invention, and I there-

fore do not intend to limit myself to the specific form shown and described.

What I claim as new and desire to secure by Letters Patent is:

1. In a current motor, the combination 35 with a pair of abutments, one located on each side of a stream, a cable extending between the abutments, a traveler mounted on the cable, a scow, a second cable connecting the scow to the traveler, a pulley to be driven, and a third cable having its ends connected to the scow and running over the driven pulley.

2. In a current motor, the combination 40 with a pair of abutments, one located on each side of a stream, a cable extending between the abutments, a traveler mounted on the cable, a scow, a second cable connecting the scow to the traveler, a pulley to be driven, pulleys mounted on the abutment, a third 45 cable having its ends connected to the scow and running over the pulleys on the abutments, and also passing around the driven pulley.

In testimony whereof I affix my signature 50 in presence of two witnesses.

CHARLES S. DONEY.
